United States Patent Office

Des. 186,511
Patented Nov. 3, 1959

186,511

ELECTRICAL INDUCTION UNIT

William P. Carpenter, Bristol, Conn., assignor to The Superior Electric Company, Bristol, Conn., a corporation of Connecticut

Application April 1, 1959, Serial No. 55,293

Term of patent 14 years

(Cl. D26—15)

Figure 1 is a front elevational view of an electrical induction unit, showing my new design, the rear being substantially a mirror image thereof;

Fig. 2 is a top plan view;

Fig. 3 is a side elevational view; and

Fig. 4 is an opposite side elevational view thereof.

I claim:

The ornamental design for an electrical induction unit, as shown and described.
